CLAIM

The ornamental design for a high back rest chair, as shown and described.

DESCRIPTION

FIG. 1 shows a front elevational view of the high back rest chair showing my new design;

FIG. 2 represents a side elevational view thereof;

FIG. 3 illustrates a rear plan view thereof;

FIG. 4 is a top plan view thereof;

FIG. 5 shows a bottom plan view of the invention thereof; and,

FIG. 6 shows an isometric view of the invention.
